ELECTRICAL INSULATION CUTTER

Matt Spinello, Rockford, Ill., assignor of one-half to Lemuel J. Wood, Rockford, Ill.

Application May 16, 1938, Serial No. 208,200

8 Claims. (Cl. 30—91)

This invention relates to a tool for cutting and removing insulation covering and insulation from electric wires.

Electricians and linemen have been accustomed to using pocket knives for cutting the cloth and rubber covering and insulation off wires. This method is slow and tedious as well as hazardous, not only from the standpoint of the danger of cutting one's fingers if the knife slips, but also because there is no way of gauging the depth of cut, and one is apt in cutting the covering to cut through the insulation of the inner wires. I am aware that several attempts have been made to devise tools to do this work but they have not been adopted because some were not adjustable to suit different needs and those that were adjustable were so designed that it took too much time to make the adjustment and obviously the workman would feel that unless he could save time over the old method there was no object in the purchase of a special tool for that purpose. Furthermore, most of the tools proposed were intended only for cutting the covering and the workman would still have to resort to the pocket knife to remove the insulation. It is therefore the principal object of my invention to provide a quickly adjustable tool designed to do both operations, the same having a blade which in one position works in a V-shaped guide to cut the covering, the blade being adjustable quickly to suit the depth of cut to be made, and which in another position projects outside the V guide and is adapted in such position to circumscribe the insulation and be used in pulling the short section of insulation thus severed off the end of the wire.

The invention is illustrated in the accompanying drawing, in which—

Figures 1 and 2 are a side and front view of the tool of my invention illustrated in the act of cutting the covering of a duplex wire;

Fig. 3 is a view similar to Figure 1 but showing the blade in an extreme position of adjustment projecting from the V guide to remove the insulation from one of the inner wires;

Fig. 4 is a bottom view, and Fig. 5 an end view of the tool, and

Fig. 6 is a longitudinal section through the tool on the line 6—6 of Fig. 5.

The same reference numerals are applied to corresponding parts throughout the views.

The tool comprises a handle 7 of wood, rubber, or any composition material, channel shaped in cross-section and having mounted in the channel thereof a channel-shaped sheet metal blade

holder 8, the side walls of which are parallel for the major portion of the length of the holder but at one end are bent outwardly away from one another to provide a V guide 9 to cooperate with the hook-shaped cutting end 10 of the blade 11. The blade 11 has a free working fit between the side walls of the channel-shaped holder 8, and is mounted for pivotal movement on a bolt 12 entered through registering holes in the handle 7 and blade holder 8 and having a nut 13 threaded on one end thereof to retain the same in place. The end of the blade holder 8 remote from the V guide 9 has the side walls thereof spread apart to the diverging relationship indicated at 14 in Fig. 4 so as to provide a wide enough throat or slot 15 in the rear end of the blade holder for adjustment of the tail end 16 of the blade relative to a ratchet 17 formed preferably as an extension of one side wall of the blade holder bent inwardly substantially at right angles toward the end 16 of the blade 11. The end portion 16 is in line with the rest of the blade 11 but bent about its longitudinal axis as indicated at 18 so that the lower edge of said end portion can engage selectively with any one of the teeth 19 of the ratchet 17. There is sufficient springiness in the blade 11 to keep the end portion 16 securely engaged with the ratchet in any position of adjustment, but one can readily and quickly shift the end portion up or down to some other position by simply pressing the end portion 16 out of engagement with the ratchet and then moving it to the position desired, whereupon it will spring back into engagement with the ratchet to lock the blade in the new position.

In operation, when the blade 11 is adjusted to cut to the proper depth, the V-shaped front end of the tool is placed over the wire as indicated in Figs. 1 and 2, and the covering 20 is cut lengthwise by movement of the tool along the wire. After the covering is slit it can be laid back to expose the inner wires 21 and 22 and cut or torn off. In cutting it off, one may use the blade 11 in the position shown in Fig. 3 and run the hooked end of the blade, which is sharpened along two sides of a V as indicated at 23 and 24, 45 circumferentially around the wire to sever the slit end section of covering from the rest of the wire. Then, with the blade 11 still in this same position, one can also use it to cut off the insulation from the inner wires 21 and 22 as shown in Fig. 3, the operation here being similar to that described for cutting the covering 20 circumferentially. Once the insulation has been cut completely around the wire, the workman can

use the hooked end 10 of the blade conveniently in pulling off the severed end portion of insulation from the wire. It is evident, therefore, that with the present tool one can do all of the operations required and the blade can be moved from one position to another so quickly that the electrician saves considerable time in working with this tool as compared with using a pocket knife. When the tool is not in use the hooked end 10 of the blade will be in a retracted position so that there is no danger of cutting one's self or having the tool damaged by contact with other tools in a tool box. The tool is furthermore made small enough so that it can be carried in the pocket so as to be just as handy and ready for use as the pocket knife. It is furthermore obvious that the construction is such that the tool can be made at very low cost and will be extremely serviceable.

20 It is believed the foregoing description conveys a good understanding of the objects and advantages of my invention. The appended claims have been drawn with a view to covering all legitimate modifications and adaptations.

25 I claim:

1. A tool for cutting and stripping insulation from electric wires comprising an elongated blade holding handle, the same having a V guide at one end thereof, an elongated blade pivotally mounted intermediate the ends thereof on said handle and having a cutting end movable in said V guide, the other end of said blade projecting from said handle and being flexible laterally relative to the handle manually for locking and 35 unlocking the same with respect to the handle and means for quickly releasably locking said blade by said manually operable flexible end in fixed relation to the handle.

2. A tool for cutting insulation on electric 40 wires comprising an elongated blade holding handle having a V guide at one end thereof, an elongated blade pivotally mounted intermediate the ends thereof on said handle and having one end constructed for cutting the insulation and the other end projecting from the adjacent end of 45 the handle for manual oscillatory adjustment of the blade, the blade being so formed and pivoted that the cutting end is not only adjustable in respect to the amount it projects into the V guide, so as to determine the depth of cut in slitting 50 insulation, but is also adjustable to an extreme position where substantially the entire cutting end projects out of the V guide end of the handle so as to adapt the same for use in cutting insulation circumferentially with respect to a 55 wire, and means cooperating with the manually operable end of the blade for locking said blade releasably in adjusted position.

3. A tool for cutting insulation on electric 60 wires comprising an elongated blade holding handle having a V guide at one end thereof, an elongated blade pivotally mounted intermediate the ends thereof on said handle and having one end constructed for cutting the insulation and the other end projecting from the adjacent end of 65 the handle for manual oscillatory adjustment of the blade, the blade being so formed and pivoted that the cutting end is not only adjustable in respect to the amount it projects into the V 70 guide, so as to determine the depth of cut in slitting insulation, but is also adjustable to an extreme position where substantially the entire cutting end projects out of the V guide end of the handle so as to adapt the same for use in cutting insulation circumferentially with respect 75

to a wire, and means for releasably locking the blade in adjusted position.

4. A tool of the character described comprising an elongated channel-shaped sheet metal blade holder having the side walls at one end thereof bent outwardly in diverging relation to form a V guide adapted to receive an electric wire in running the tool lengthwise of the wire to slit the insulation covering thereon, an elongated flat blade having a close working fit between the side walls of the holder and pivoted intermediate the ends thereof in the holder for oscillatory movement so as to adjust one end of the blade outwardly from the apex of the V guide according to the depth of cut to be made, said end having a cutting edge thereon adapted for slitting insulation covering on a wire, the other end of the blade protruding from the adjacent end of the holder for manual adjustment of the blade, the adjacent end of said holder having one of its side walls bent in diverging relation to the other side wall to permit lateral deflection of the manually adjustable end of the blade in the holder to and from a locked position of adjustment, and means on one side wall of said holder for releasably securing the last-named end of said blade in adjusted position relative to the holder.

5. A tool of the character described comprising an elongated channel-shaped sheet metal blade holder having the side walls at one end thereof bent outwardly in diverging relation to form a V guide adapted to receive an electric wire in running the tool lengthwise of the wire to slit the insulation covering thereon, an elongated flat blade having a close working fit between the side walls of the holder and pivoted intermediate the ends thereof in the holder for oscillatory movement so as to adjust one end of the blade outwardly from the apex of the V guide according to the depth of cut to be made, said end having a cutting edge thereon adapted for slitting insulation covering on a wire, the other end of the blade protruding from the adjacent end of the holder for manual adjustment of the blade, the last named end of the blade holder having an inturned flange, the edge of which is formed to provide a ratchet, and the last named end of the blade having a lower edge portion normally engaging the ratchet to hold the blade in adjusted position, said blade end being spring pressed toward engagement with the ratchet but being movable out of engagement therewith manually to permit adjustment of the blade as desired.

6. A tool of the character described comprising an elongated channel-shaped sheet metal blade holder having the side walls at one end thereof bent outwardly in diverging relation to form a V guide adapted to receive an electric wire in running the tool lengthwise of the wire to slit the insulation covering thereon, an elongated flat blade having a close working fit between the side walls of the holder and pivoted intermediate the ends thereof in the holder for oscillatory movement so as to adjust one end of the blade outwardly from the apex of the V guide according to the depth of cut to be made, said end having a cutting edge thereon adapted for slitting insulation covering on a wire, the other end of the blade protruding from the adjacent end of the holder for manual adjustment of the blade, the last named end of the blade holder being formed so that the end portions of the side walls thereof diverge so as to form a wide enough throat to permit laterally springing the last named end of

- the blade, the last named end of the blade being twisted into acute angled relationship to the rest of the blade, and one side wall of the blade holder having the end portion thereof formed to provide an inwardly bent flange, the edge of which is further formed to provide a ratchet for engagement with the lower edge of the twisted end portion of the blade, the twisted end portion of the blade being normally disposed in engagement with the ratchet to hold the blade in adjusted position but being springable laterally out of engagement with the ratchet to permit oscillatory adjustment of the blade.
7. A tool of the character described comprising an elongated channel-shaped sheet metal blade holder having the side walls at one end thereof bent outwardly in diverging relation to form a V guide adapted to receive an electric wire in running the tool lengthwise of the wire to slit the insulation covering thereon, an elongated flat blade having a close working fit between the side walls of the holder and pivoted intermediate the ends thereof in the holder for oscillatory movement so as to adjust one end of the blade outwardly from the apex of the V guide according to the depth of cut to be made, said end having a cutting edge thereon adapted for slitting insulation covering on a wire, the other end of the blade protruding from the adjacent end of the holder for manual adjustment of the blade, means for releasably securing the blade in adjusted position, handle grip means for engagement with the opposite side walls of the blade holder, and a bolt ex-

tending through registering holes in the handle grip means and the side walls of the holder and also in the blade whereby to secure the handle means to the holder and also provide the intermediate pivot for the blade.

8. A tool of the character described comprising an elongated channel-shaped sheet metal blade holder having the side walls at one end thereof bent outwardly in diverging relation to form a V guide adapted to receive an electric wire in running the tool lengthwise of the wire to slit the insulation covering thereon, an elongated flat blade having a close working fit between the side walls of the holder and pivoted intermediate the ends thereof in the holder for oscillatory movement so as to adjust one end of the blade outwardly from the apex of the V guide according to the depth of cut to be made, said end having a cutting edge thereon adapted for slitting insulation covering on a wire, the other end of the blade protruding from the adjacent end of the holder for manual adjustment of the blade, means for releasably securing the blade in adjusted position, a handle of channel-shaped cross-section fitting over the blade holder with the side walls thereof in abutment with the outside of the side walls of said blade holder, and a single bolt extending through registering holes provided in the side walls of the handle and blade holder and also in the blade whereby to secure the handle to the holder and also provide the pivot for the blade.

MATT SPINELLO.
